(57) **CLAIM**

The ornamental design for a paintball marker stand, as shown and described.

DESCRIPTION

Stand for positioning a paintball marker to provide a stable platform.

FIG. 1 is a perspective view of a paintball marker stand of the invention in an open form;

FIG. 2 is an elevational view of a first side of the paintball marker stand of FIG. 1;

FIG. 3 is an elevational view of a second side of the paintball marker stand of FIG. 1;

FIG. 4 is a view of a front end of the paintball marker stand of FIG. 1;

FIG. 5 is a view of a rear end of the paintball marker stand of FIG. 1;

FIG. 6 is a top plan view of the paintball marker stand of FIG. 1;

FIG. 7 is a bottom plan view of the paintball marker stand of FIG. 1;

FIG. 8 is an elevational view of a first side of the paintball marker stand in a closed form;

FIG. 9 is an elevational view of a second side of the paintball marker stand in a closed form;

FIG. 10 is a view of a front end of the paintball marker stand in a closed form;

FIG. 11 is a view of a rear end of the paintball marker stand in a closed form;

FIG. 12 is a top plan view of the paintball marker stand in a closed form; and,

FIG. 13 is a bottom plan view of the paintball marker stand in a closed form.
